REVERSING RHEOSTAT

Edwin N. Lightfoot, Wauwatosa, and Theodore F. Rosing, Whitefish Bay, Wis., assignors to Cutler-Hammer, Inc., Milwaukee, Wis., a corporation of Delaware

Application October 7, 1943, Serial No. 505,266

14 Claims.

(Cl. 201—62)

This invention relates to improvements in rheostats of the reversing type.

A primary object of the invention is to improve and simplify the construction and operation of rheostats of the aforementioned character.

Another object is to provide a simple form of rheostat which is operable to regulate and reverse the current through a load circuit from full positive to full negative through any desired number of steps, including complete interruption of said load circuit at an intermediate point on the rheostat corresponding to substantially zero potential.

Another object is to provide a reversing rheostat which is adapted to be power operated, subject to selective manual control; or alternatively adapted for direct manual operation at will, as in the event of failure of the power operating means.

Another object is to provide an intermittent and reversing type of solenoid operating mechanism of novel form.

Another and more specific object is to provide for remote manual pushbutton control of said solenoid operating mechanism.

Another object is to provide a reversing rheostat embodying a common set of resistance sections electrically connected with a corresponding number of contact segments, the contact segments being so arranged as to be traversed by a pair of contact brushes operable simultaneously in opposite directions.

Another object is to provide such a rheostat affording a maximum number of steps of resistance variation with a minimum number of resistance sections.

Another object is to provide novel means for manually adjusting or preselecting the speed of operation of the reversing rheostat.

Various other objects and advantages of the invention will hereinafter appear.

The accompanying drawing illustrates schematically and diagrammatically a preferred embodiment of our invention; it being understood that the embodiment illustrated is susceptible of modification in respect of certain structural details thereof without departing from the scope of the appended claims.

In the drawing, Figure 1 is a schematic and diagrammatic illustration of a reversing rheostat embodying our invention.

Fig. 2 is a diagrammatic illustration of the form and arrangement of certain of the parts shown in Fig. 1, and showing in detail certain

additional elements of the timing mechanism, and

Fig. 3 is a fragmentary diagrammatic illustration, with the contact brushes in their neutral or "off" position, and showing one brush in staggered or offset relationship to the other, whereby the two brushes are adapted to engage the several successive contact segments in alternate sequence instead of simultaneously, thus substantially doubling the number of resistance gradations afforded by the rheostat.

Referring to Fig. 1, the numeral 5 designates a winding in a suitable load circuit through which it is desired to effect a full positive or full negative flow of current, or any desired value of positive or negative current; the transition from positive to negative flow of current, or vice versa, being effected in each case when the current is at a minimum or substantially zero value. In 20 the device herein illustrated provision is made for completely interrupting the flow of current at the transition point of minimum value of the positive or negative current flow.

The winding 5 may be assumed to represent 25 the field coil of a generator employed in a de-gaussing system. Line L¹ and L² represent a suitable source of current supply for coil 5, and the numerals 6^a, 6^b designate resistances to which lines L¹ and L² are respectively connected at the 30 points 6^c and 6^d. The terminals 5^a and 5^b of coil 5 are respectively connected by flexible conductors 7 and 8 to contact brushes 9 and 10; the latter in the respective positions thereof shown in Fig. 1 providing for a full positive flow of current through said coil, said circuit extending from line L¹ through point 6^c and brush 9, conductor 7 through point 5^a and coil 5, and through point 5^b, conductor 8, brush 10 and point 6^d to line L².

As best illustrated in Fig. 3, resistances 6^a and 40 6^b are divided into any desired number of sections 6^e, the adjacent ends or terminals of each two sections 6^e being electrically connected to one of the multiplicity of contact blocks or segments 11. In the diagrammatic illustration in 45 Fig. 3 the resistance sections 6^e are shown interposed between the pairs of contact segments 11, whereas actually said segments 11 are in practice located quite close to each other, so that each brush 9 or 10 will engage the next adjacent segment prior to disengagement thereof from the presently engaged segment in each direction of movement of said brushes. The contact segments 11 are spaced the desired distance from each other by interposing suitable insulating plates or blocks (not shown) therebetween, the

resistance sections being terminally connected to the spaced contact segments 11 in a manner to afford proper clearance for brushes 9 and 10.

The groups 6^a and 6^b (Fig. 1) of resistance sections 6^e (Fig. 3) are preferably separated a substantial distance from each other, as by means of an insulating block or spacer 12, so that at approximately the mid-length of the complete range of travel of the brushes 9 and 10 both of the same will be disengaged from all of the contact segments 11 (see Fig. 3). As will be apparent from Figs. 1 and 3, when contact brushes 9 and 10 are engaged respectively with the contact segments 11, 11 at opposite ends of block 12 all of the resistance sections 6^e will be included in circuit in series with coil 5, whereby the current through the latter is reduced to its minimum value; and in practice the arrangement is preferably such as to provide substantially zero potential across the terminals of coil 5 under the condition just mentioned. Also it will be understood that the direction of current flow (positive or negative) through coil 5 will depend upon whether brushes 9 and 10 are respectively engaged with the contact segments 11 at the right-hand and left-hand sides of block 12 (see Fig. 3) to provide a positive flow, or with those at the left-hand and right-hand sides of said block to provide a negative flow.

Any suitable means (not shown) may be provided for manually interrupting the supply of current from lines L¹, L². Assuming completion of the circuit from the source of supply through lines L¹, L², and with the various elements of the system in the positions thereof shown in Fig. 1, it will be apparent that coil 5 is subjected to the full positive potential of lines L¹, L² as aforescribed. As shown, the contact brush 9 is carried by a nut 9^a which is adapted to travel upon a rotatable threaded shaft 13 having suitable fixed bearings 14 and 15; brush 9 being insulated from nut 9^a in any suitable manner, as indicated at 9^b. Also attached to nut 9^a, but insulated therefrom as shown at 9^c, is an element 9^d the end portion 9^e of which acts in the position thereof illustrated to effect opening of a limit switch 16, the bridging contactor 16^a of which is normally biased to its closed position by a compression spring 17. With contactor 16^a thus disengaged from the stationary contacts of limit switch 16 the contact brushes 9 and 10 cannot be driven by the power operated means beyond the extreme positions thereof illustrated.

However, the power operated means may be utilized, under control of one of the manually operated push buttons hereinafter described, to effect step by step movement of contact brushes 9 and 10 jointly toward or to their other respective extreme positions. Thus the contact brush 10 is carried by a nut 10^a, but insulated from the latter as shown at 10^b; the nut 10^a being adapted for cooperative engagement with a rotatable threaded shaft 18 having suitable fixed bearings 19 and 20. Also attached to nut 10^a, but insulated therefrom as shown at 10^c, is an element 10^d the end portion 10^e of which acts, in the opposite extreme position of contact brush 10 from that illustrated, to effect opening of a limit switch 21, the bridging contactor 21^a of which is normally biased to the closed position thereof illustrated, as by means of compression spring 22.

The power operating means for contact brushes 9 and 10 comprises a pair of relatively small gears 23 and 24 keyed or otherwise rigidly connected to the reduced end portions of shafts 13 and 18, said

gears being arranged to mesh continuously with a relatively larger gear 25 positioned therebetween. Gear 25 is rigidly attached to one end of a shaft 26 which is rotatably supported in suitable bearings (not shown). Shaft 26 projects outwardly from gear 25 and has rigidly attached thereto a pair of like toothed ratchet wheels 27, 27. Said wheels 27 are reversely arranged with respect to each other, so that the teeth, marked 27^a, of one are arranged to be engaged by a pawl 28^a, carried by the core of a solenoid 28, the coil of which is designated by numeral 28^b. Thus upon energization of coil 28^b pawl 28^a is moved upwardly from the normal position shown in Fig. 3 into engagement with one of the teeth 27^a, thereby effecting a predetermined degree of clockwise rotation of shaft 26 and gear wheel 25, with consequent counterclockwise rotation of gears 23 and 24 and of the respective shafts 13 and 18 associated with the latter.

Inasmuch as shaft 13 is provided with a right-hand thread and shaft 18 is provided with a left-hand thread such clockwise rotation thereof will result in downward movement of brush 9 (Fig. 1) and upward movement of brush 10 to increase in a step by step manner the number of sections of the resistances 6^a and 6^b included in the circuit of coil 5, pending attainment of the minimum value of the positive current at the transition point 12 of the rheostat, whereupon the minimum value of negative current is first applied to coil 5, such value being gradually increased until full negative current is applied when brush 9 is in its lower extreme position and brush 10 is in its upper extreme position.

When brush 10 has reached the extreme position thereof last mentioned the end portion 10^e of element 10^d associated with nut 10^a will have engaged and opened contactor 21^a of limit switch 21 to prevent overtravel of the brushes 10 and 9 to insure against interruption of the circuit of coil 5 under such conditions.

With brush 10 in its upper extreme position and brush 9 in its lower extreme position (Fig. 1), or with said brushes in any of their respective intermediate positions, simultaneous movement of brush 9 upwardly and of brush 10 downwardly may be effected by intermittent energization of coil 29^b of solenoid 29, the core of which carries a pawl 29^a adapted for engagement with the teeth, marked 27^b, of the right-hand ratchet wheel 27 in Fig. 2. Upon each upward movement of pawl 29^a gear 25 is rotated to a predetermined degree in a counterclockwise direction, with consequent clockwise rotation of shafts 13 and 18 for the purpose just mentioned.

The cores of solenoids 28 and 29 are respectively biased toward the disengaged positions thereof shown in Fig. 2, as by means of a pair of coiled tension springs 30 and 31 attached to downward extensions 28^c and 29^c; said extensions being respectively pivotally connected at 32^a and 32^b to oppositely extending arms of a lever 32, which is pivotally supported at its mid-length, as by means of a pin 33. The intermediate or pivotal supporting portion of lever 32 is enlarged as shown at 32^c, and said enlarged portion is provided with a downwardly facing double-inclined cam surface or notch 32^d, which is adapted, in the intermediate or neutral position of lever 32, to accommodate the upper end of a stud or pin 34^a attached to a switch contactor 34. Contactor 34 is pivoted at 34^b, and is normally biased out of engagement with its associated stationary contact 34^c, as by means of a coiled compression spring 34^d. The

arrangement is such that upon upward movement of either core 28 or 29 the double-inclined cam surface 32^d will act upon stud 34^a to effect engagement of contactor 34 with stationary contact 34^c.

Operation of the system will now be described with particular reference to the diagram of Fig. 1. With the various elements in the respective positions illustrated, wherein coil 5 is subjected to the full positive current from lines L¹ and L², step by step movement of brush 9 downwardly and of brush 10 upwardly, to decrease the value of the positive current, may be effected by manually depressing and holding the pushbutton 35, whereby its normally open stationary contacts 35^a are bridged by contactor 35^b. This completes an energizing circuit for the coil 29^b of solenoid 29, said circuit extending from line L¹ by conductor 36 and a suitable fuse or similar protective device 37, by conductor 38 through the normally closed contacts 39^a of a relay 39 (the operating coil of which is designated by numeral 39^b), by conductor 40 through the contacts 21^a of limit switch 21 (which is then in its normally closed position, as illustrated), by conductor 41 to and through said coil 29^b, by conductor 42 through said pushbutton contacts 35^a and contactor 35^b, thence by conductor 43 through the normally closed contacts 44^c and contactor 44^b of a second pushbutton switch 44, and by conductors 45 and 46 through fuse 47 and conductor 48 to line L².

Upon energization of coil 29^b in the manner just described the pawl 29^a is moved upwardly to effect a predetermined degree of counterclockwise rotation of shaft 26 and the parts carried thereby, with consequent clockwise rotation of shafts 13 and 18 to effect downward movement of brush 9 and upward movement of brush 10. It may be assumed that such step of movement of brushes 9 and 10 simultaneously will only result in including one of the sections 6^e within the circuit of coil 5, to decrease to a predetermined degree the value of positive current supplied to coil 5.

Upon such upward movement of pawl 29^a the lever 32 (Fig. 2) is simultaneously rotated counterclockwise to such a degree that the left-hand inclined surface of notch 32^d will act upon stud 34^a to effect engagement of contactor 34 with stationary contact 34^c. As shown in Fig. 1, this will complete an energizing circuit for the operating coil 39^b of relay 39, which circuit extends from line L¹ by conductor 36 through fuse 37, conductors 49 and 50 through said coil 39^b, conductor 51 through contact 34^c and contactor 34, and by conductor 52 to line L². The normally closed contacts 39^a of relay 39 are thus opened to effect interruption of the aforescribed circuit of coil 29^b of solenoid 29, with consequent retraction of pawl 29^a and lever 32 to the neutral positions thereof shown in Fig. 2, whereby contactor 34 is disengaged from contact 34^c to interrupt the energizing circuit of coil 39^b.

In the absence of any additional elements such interruption of the energizing circuit of coil 39^b would result in immediate reclosure of the normally closed contacts 39^a to again complete the energizing circuit of solenoid coil 29^b (assuming manual retention of pushbutton contactor 35^b in engagement with contacts 35^a). However, we provide a suitable condenser 53 connected in shunt relationship to coil 39^b, whereby said condenser is charged to a degree corresponding to the period of normal energization of said coil 39^b, and upon interruption of the normal energizing circuit of the latter condenser 53 will discharge through the

loop containing it and coil 39^b to maintain the relay contacts open for a predetermined period of time. By thus delaying the reclosure of contacts 39^a of relay 39 the number of upward or operating strokes of pawl 29^a per unit of time may be substantially reduced, to thereby correspondingly reduce the rate of change in the value of current supplied to coil 5.

We also prefer to provide a rheostat 54 connected in said loop in series with condenser 53; the contactor 55 of said rheostat being manually adjustable to provide for variation of the rate of charging of condenser 53, and to correspondingly vary the total charge of the latter during the normal period of energization of coil 39^b. In this manner the period during which contacts 39^a of relay 39 are held open after disengagement of contactor 34 from contact 34^c may be varied throughout a relatively wide range, to thereby provide a correspondingly wide range of variation in the rate of change of the value of current supplied to coil 5. Thus if rheostat contactor 55 is moved toward the left to decrease the value of resistance 54 in circuit the rate of charging of condenser 53 will be increased to maintain coil 39^b energized for a longer period; and the opposite effect results from movement of contactor 55 toward the right. The range of variation in the rate of change in value of current in coil 5 may of course be modified by substitution of a condenser and/or rheostat 54 of different value or caliber.

Although I have illustrated a slidable contactor type of rheostat 54 it will be apparent that I may employ any other suitable method of varying the value of the timing resistance, as, for example, a group of resistance sections with taps in combination with a flexible connector associated with said taps to short circuit any desired number of the resistance sections.

If the pushbutton 35 is manually held in its depressed position the pawl 29^a will be intermittently moved upwardly to effect simultaneous downward movement of brush 9 and upward movement of brush 10 at a rate determined by the adjustment of rheostat contactor 55, each such movement of brushes 9 and 10 jointly being adapted to effect inclusion in the positive current circuit of coil 5 an additional section 6^e of the resistance, until just prior to the mid-length of the total range of travel of the two brushes when all of the resistance sections 6^e will be included in such circuit, to thereby reduce the positive current through coil 5 to its minimum or substantially zero value. Thereafter one or both of the brushes 9 and 10 will move onto the insulating block 12 to insure complete interruption of the circuit of coil 5 (see Fig. 3).

Upon continuous downward movement of brush 9 and upward movement of brush 10 the brush 9 will engage the first contact segment 11 at the left-hand side of block 12 (Fig. 3) while brush 10 is still engaged with the first contact segment 11 at the right-hand side of said block, thus effecting completion of the negative current circuit of coil 5 with all of the resistance sections 6^e included therein, whereby said negative current is initially of minimum or substantially zero value. Thereafter the resistance sections 6^e will be excluded in sequence from the negative current circuit, until at the lowermost position of brush 9 and the uppermost position of brush 10 (as controlled by the operation of limit switch 21 as aforescribed) all of the resistance sections 6^e will be excluded from

circuit to thereby subject coil 5 to the full value of negative current.

It is to be understood that during such step by step movement or adjustment of the positions of brushes 9 and 10 (in either of their respective directions) the rheostat contactor 55 may be manually adjusted to either increase or decrease the rate of movement of the brushes, to thereby provide for decreasing or increasing the period of time required for change from one character and/or value to another of the current supplied to coil 5.

With brush 9 in its lowermost position and brush 10 in its uppermost position, or with said brushes jointly in any other than the respective extreme positions thereof shown in Fig. 1, simultaneous movement of brush 9 upwardly and brush 10 downwardly may be effected by manually depressing and holding pushbutton 44 so that its contactor 44^b is engaged with stationary contacts 44^a (the pushbutton 35, of course, having been released to permit return thereof to its normal position illustrated). Such depression of pushbutton 44 will complete an energizing circuit for the coil 28^b of solenoid 28, which circuit may be traced from line L² by conductor 48 through fuse 47, by conductors 46 and 56, stationary contacts 35^c and contactor 35^b of pushbutton switch 35, by conductor 57 through stationary contacts 44^a and contactor 44^b of pushbutton switch 44, by conductor 58 through the coil 28^b of solenoid 28, by conductor 59 through the normally closed contacts of limit switch 16, by conductor 40 through contacts 39^a of relay 39, by conductors 38 and 49 through fuse 37, and by conductor 36 to line L¹.

In practice we prefer to provide a fixed resistance 60 and a condenser 61 connected in series with each other across the terminals of coils 28^b and 29^b. If the limit switches 16 and 21 are both closed (as in any intermediate positions of brushes 9 and 10) upon release of the last active pushbutton switch 35 or 44 a discharge circuit through the resistance 60, condenser 21 and the inactive coil 29^b or 28^b, as the case may be, is provided for the last active coil 29^b or 28^b. This has the effect of minimizing arcing at the contacts of pushbuttons 35 or 44 and at the contacts 39^a of relay 39.

As shown in Figs. 1 and 2 we prefer to non-rotatably attach to the outer end of shaft 26 a manually rotatable knob 62, whereby manual adjustment or movement of brushes 9 and 10 may be effected at will entirely independently of the power operating means of the rheostat. This feature is of importance in the event of failure or derangement of any part of the power operating means. Knob 62 is also useful for enabling manual presetting of the brushes 9 and 10 of the rheostat at the desired positions thereof prior to completion of the rheostat circuit from the source of current supply which is here represented by lines L¹, L².

While we have herein illustrated a rheostat of the series type in which the circuit from the line through coil 5 is opened just prior to movement of brushes 9 and 10 to their neutral or intermediate position, it will be apparent to those skilled in the art that what is commonly known as a potentiometer connection may be employed, where preferred for some specific installation, by substituting for insulating block 12 a conductive block which will maintain the circuit through the resistor 6^a, 6^b from one line to the other.

Furthermore, where a conductive block is used such block has the further function of short-cir-

cuiting coil 5 before the direction of current flow therein is reversed, thereby affording a discharge path for any energy in the magnetic field, if it is found desirable to provide some means for absorbing such energy; thus affording what is commonly known as a discharge circuit. Such operation will take place at a time when the current is reduced substantially to zero so that the magnetic energy is relatively small but nevertheless requires some means to guard against arcing or insulation failure consequent upon high discharge voltages.

We claim:

1. In a reversing rheostat, in combination, a single set of resistance sections, a single set of fixed spaced contact segments respectively electrically connected with said resistance sections, the end contact segments of said set being respectively connected to opposite poles of a source of current supply, a pair of contact brushes common to said contact segments and adapted to cooperate therewith, means for effecting movement of said contact brushes jointly in opposite directions respectively throughout the total length of said set of contact segments, a translating device including a coil the terminals of which are respectively connected with said contact brushes, whereby in one extreme position of the respective brushes said coil is subjected to the full positive potential of said source of current supply and in the other extreme position of the respective brushes said coil is subjected to the full negative potential of said source of current supply, and whereby at the midpoint of the total range of movement of said brushes jointly they are subjected to substantially zero potential wherefore no current flows through said coil.

2. In a reversing rheostat, in combination, a single set of resistance sections, a single set of fixed spaced contact segments respectively electrically connected with said resistance sections, the end contact segments of said set being respectively connected to opposite poles of a source of current supply, a pair of contact brushes common to said contact segments and adapted to cooperate therewith, means for effecting movement of said contact brushes jointly in opposite directions respectively throughout the total length of said set of contact segments, a translating device including a coil the terminals of which are respectively connected with said contact brushes, whereby in one extreme position of the respective brushes said coil is subjected to the full positive potential of said source of current supply and in the other extreme position of the respective brushes said coil is subjected to the full negative potential of said source of current supply, whereby at the midpoint of the total range of movement of said brushes jointly they are subjected to substantially zero potential wherefore no current flows through said coil, and power operated means reversible at will for effecting movement of said brushes jointly toward and from either of their respective extreme positions.

3. In a reversing rheostat, in combination, a single set of resistance sections, a single set of fixed spaced contact segments respectively electrically connected with said resistance sections, the end contact segments of said set being respectively connected to opposite poles of a source of current supply, a pair of contact brushes common to said contact segments and adapted to cooperate therewith, means for effecting movement of said contact brushes jointly in opposite directions respectively, a translating device in-

cluding a coil the terminals of which are respectively connected with said contact brushes, whereby in one extreme position of the respective brushes said coil is subjected to the full positive potential of said source of current supply and in the other extreme position of the respective brushes said coil is subjected to the full negative potential of said source of current supply, whereby at the midpoint of the total range of movement of said brushes jointly they are subjected to substantially zero potential wherefore no current flows through said coil, power operated means reversible at will for effecting movement of said brushes jointly toward and from either of their respective extreme positions, said last mentioned means including a pair of oppositely threaded parallel rotatable shafts, traveling nuts on said shafts in a predetermined relationship to each other, said brushes being attached to the respective nuts for movement with the latter, a third shaft geared to said shafts first mentioned, a pair of oppositely toothed ratchet wheels non-rotatably attached to said third shaft, a solenoid including a coil, a core and a pawl associated with each ratchet wheel, and a pair of pushbutton switches selectively operable to control intermittent energization of the respective solenoid coils.

4. In a reversing rheostat, in combination, a single set of resistance sections, a single set of fixed spaced contact segments respectively electrically connected with said resistance sections, the end contact segments of said set being respectively connected to opposite poles of a source of current supply, a pair of contact brushes common to said contact segments and adapted to cooperate therewith, means for effecting movement of said contact brushes jointly in opposite directions respectively, a translating device including a coil the terminals of which are respectively connected with said contact brushes, whereby in one extreme position of the respective brushes said coil is subjected to the full positive potential of said source of current supply and in the other extreme position of the respective brushes said coil is subjected to the full negative potential of said source of current supply, whereby at the midpoint of the total range of movement of said brushes jointly they are subjected to substantially zero potential wherefore no current flows through said coil, power operated means reversible at will for effecting movement of said brushes jointly toward and from either of their respective extreme positions, said last mentioned means including a pair of oppositely threaded parallel rotatable shafts, traveling nuts on said shafts in a predetermined relationship to each other, said brushes being attached to the respective nuts for movement with the latter, a third shaft geared to said shafts first mentioned, a pair of oppositely toothed ratchet wheels non-rotatably attached to said third shaft, a solenoid including a coil, a core and a pawl associated with each ratchet wheel, a pair of pushbutton switches selectively operable manually to provide for operating energization of one or the other of the solenoid coils, means comprising a cam-operated normally open switch adapted to be closed automatically upon operating movement of either of the solenoid cores, a normally closed electromagnetically operable relay adapted to be energized upon each closure of said last mentioned switch, said relay when opened being adapted to effect deenergization of either of said solenoid coils to provide for resetting of its re-

spective pawl and reopening of said normally open switch whereby the energizing circuit of said relay is interrupted, and said relay when deenergized effecting reenergization of the active solenoid coil to provide a repeated operation of the pawl associated therewith.

5. In a reversing rheostat, in combination, a single set of resistance sections, a single set of fixed spaced contact segments respectively electrically connected with said resistance sections, the end contact segments of said set being respectively connected to opposite poles of a source of current supply, a pair of contact brushes common to said contact segments and adapted to cooperate therewith, means for effecting movement of said contact brushes jointly in opposite directions respectively, a translating device including a coil the terminals of which are respectively connected with said contact brushes, whereby in one extreme position of the respective brushes said coil is subjected to the full positive potential of said source of current supply and in the other extreme position of the respective brushes said coil is subjected to the full negative potential of said source of current supply, whereby at the midpoint of the total range of movement of said brushes jointly they are subjected to substantially zero potential wherefore no current flows through said coil, power operated means reversible at will for effecting movement of said brushes jointly toward and from either of their respective extreme positions, said last mentioned means including a pair of oppositely threaded parallel rotatable shafts, traveling nuts on said shafts in a predetermined relationship to each other, said brushes being attached to the respective nuts for movement with the latter, a third shaft geared to said shafts first mentioned, a pair of oppositely toothed ratchet wheels non-rotatably attached to said third shaft, a solenoid including a coil, a core and a pawl associated with each ratchet wheel, a pair of pushbutton switches selectively operable manually to provide for operating energization of one or the other of the solenoid coils, means comprising a cam-operated normally open switch adapted to be closed automatically upon operating movement of either of the solenoid cores, a normally closed electromagnetically operable relay adapted to be energized upon each closure of said last mentioned switch, said relay when opened being adapted to effect deenergization of either of said solenoid coils to provide for resetting of its respective pawl and reopening of said normally open switch whereby the energizing circuit of said relay is interrupted, said relay when deenergized effecting reenergization of the active solenoid coil to provide a repeated operation of the pawl associated therewith, and adjustable means associated with said relay to delay reclosure thereof upon interruption of its energizing circuit, whereby the rate of movement of said brushes jointly by said power operated means may be preselected.

6. In a reversing rheostat, in combination, a single set of resistance sections, a single set of fixed spaced contact segments respectively electrically connected with said resistance sections, the end contact segments of said set being respectively connected to opposite poles of a source of current supply, a pair of contact brushes common to said contact segments and adapted to cooperate therewith, means for effecting movement of said contact brushes jointly in opposite directions respectively, a translating device including a coil the terminals of which are respectively

connected with said contact brushes, whereby in one extreme position of the respective brushes said coil is subjected to the full positive potential of said source of current supply and in the other extreme position of the respective brushes said coil is subjected to the full negative potential of said source of current supply, whereby at the midpoint of the total range of movement of said brushes jointly they are subjected to substantially zero potential wherefore no current flows through said coil, power operated means reversible at will for effecting movement of said brushes jointly toward and from either of their respective extreme positions, said last mentioned means including a pair of oppositely threaded parallel rotatable shafts, traveling nuts on said shafts in a predetermined relationship to each other, said brushes being attached to the respective nuts for movement with the latter, a third shaft geared to said shafts first mentioned, a pair of oppositely toothed ratchet wheels non-rotatably attached to said third shaft, a solenoid including a coil, a core and a pawl associated with each ratchet wheel, a pair of pushbutton switches selectively operable manually to provide for operating energization of one or the other of the solenoid coils, means comprising a cam-operated normally open switch adapted to be closed automatically upon operating movement of either of the solenoid cores, a normally closed electromagnetically operable relay adapted to be energized upon each closure of said last mentioned switch, said relay when opened being adapted to effect deenergization of either of said solenoid coils to provide for resetting of its respective pawl and reopening of said normally open switch whereby the energizing circuit of said relay is interrupted, said relay when deenergized effecting reenergization of the active solenoid coil to provide a repeated operation of the pawl associated therewith, adjustable means associated with said relay to delay reclosure thereof upon interruption of its energizing circuit, whereby the rate of movement of said brushes jointly by said power operated means may be preselected, and said adjustable means comprising a condenser and an adjustable resistance connected in a closed loop in series with each other and with the coil of said relay to provide for maintaining the operating energization of the latter for a predetermined period of time after interruption of the normal energizing circuit of said relay coil.

7. In a reversing rheostat, in combination, a single set of resistance sections, a single set of spaced contact segments electrically connected in series relationship to each other through the medium of the respective resistance sections, said contact segments being arranged in a line, the contact segments at opposite ends of said line being respectively connected to opposite poles of a suitable source of current supply, a pair of contact brushes common to and jointly cooperable with said contact segments throughout the length of said line, a translating device including a coil whose terminals are respectively connected with said brushes to provide for passage of current to said coil from said source of supply, the arrangement being such that when said brushes are respectively engaged in one relation with opposite end contact segments of said line said coil will be subjected to the full positive potential of said source, and when said brushes are respectively reversed in position with respect to said end contact segments said coil will be subjected to the full negative potential of said source, of means

for effecting movement of said brushes simultaneously from each of their respective extreme positions to their other extreme positions, and vice versa, across the intermediate contact segments of the line, whereby the variation in character and value of said change from full positive to full negative value, and vice versa, of the current supplied to said coil may be effected in increments corresponding to the resistance value or 10 values of said multiplicity of resistance sections.

8. In a reversing rheostat, in combination, a multiplicity of resistance sections, contact segments electrically connected in series relationship through the medium of the respective resistance sections, 15 said contact segments being arranged in a straight line in fixed spaced relationship to each other, the contact segments at opposite ends of said line being respectively connected to opposite poles of a suitable source of current supply, 20 a pair of contact brushes movable simultaneously in opposite directions in slidable engagement with different portions of the respective contact segments throughout the total length of said line, a translating device including a coil whose terminals are respectively connected with said brushes to provide for passage of current through said coil from said source of supply, the arrangement being such that when said brushes are respectively in one of their extreme positions full positive current is supplied to said coil and when the same are respectively in the other of their extreme positions full negative current is supplied to said coil, said brushes cooperating with said segments and said resistance sections to effect transition from full positive to full negative current in a step by step manner, including reduction of said current to substantially zero value at the midpoint of the total range of travel of said brushes jointly, power operated means for 30 effecting the aforementioned simultaneous opposite movement of said brushes in either direction throughout their total range, and associated means for automatically controlling said power operated means to prevent overtravel of said 35 brushes at each of their extreme positions.

9. In a reversing rheostat, in combination, a multiplicity of stationary contact segments arranged in a straight line in fixed spaced relationship to each other, a multiplicity of resistance sections the terminals of which are connected to said contact segments in series relationship to each other, a pair of current supply lines respectively connected to the opposite end contact segments, a pair of contact brushes slidably engageable with said contact segments at opposite side edges thereof, a translating device including a coil the terminals of which are connected to the respective brushes, each of said contact brushes being movable into and out of engagement with all of said contact segments selectively, means for effecting movement of said contact brushes simultaneously in opposite directions from each end contact segment to the other, said means comprising a pair of oppositely threaded shafts, 55 traveling nuts on said shafts, each nut having one of said brushes attached thereto for movement therewith, means for effecting intermittent rotation of said shafts jointly in one direction or the other, said means comprising a third shaft and gearing between the same and said shafts first mentioned, a pair of oppositely toothed ratchet wheels non-rotatably attached to said third shaft, a solenoid including a coil, a core and a pawl associated with one of said ratchet 60 wheels, said pawls being normally biased to posi- 65 70 75

tions affording clearance for the respective ratchet wheels, one of said solenoids being adapted upon intermittent energization of its coil to effect step by step movement of said brushes jointly toward the respective extreme positions thereof providing full positive energization of said first mentioned coil, the other solenoid when intermittently energized being adapted to effect step by step movement of said brushes jointly toward their opposite extreme positions providing full negative energization of said first mentioned coil, said brushes at the mid-point of their complete range of travel being subjected to substantially zero potential so that no current will be supplied to said first mentioned coil, and means including a pair of pushbutton switches selectively operable manually to provide for intermittent operating energization of one or the other of said solenoids.

10. In a reversing rheostat, in combination, a multiplicity of stationary contact segments arranged in a straight line in fixed spaced relationship to each other, a multiplicity of resistance sections the terminals of which are connected to said contact segments in series relationship to each other, a pair of current supply lines respectively connected to the opposite end contact segments, a pair of contact brushes slidably engageable with said contact segments at opposite side edges thereof, a translating device including a coil the terminals of which are connected to the respective brushes, each of said contact brushes being movable into and out of engagement with all of said contact segments selectively, means for effecting movement of said contact brushes simultaneously in opposite directions from each end contact segment to the other, said means comprising a pair of oppositely threaded shafts, traveling nuts on said shafts, each nut having one of said brushes attached thereto for movement therewith, means for effecting intermittent rotation of said shafts jointly in one direction or the other, said means comprising a third shaft and gearing between the same and said shafts first mentioned, a pair of oppositely toothed ratchet wheels non-rotatably attached to said third shaft, a solenoid including a coil, a core and a pawl associated with each of said ratchet wheels, said pawls being normally biased to positions affording clearance for the respective ratchet wheels, one of said solenoids being adapted upon intermittent energization of its coil to effect step by step movement of said brushes jointly toward the respective extreme positions thereof providing full positive energization of said first mentioned coil, the other solenoid when intermittently energized being adapted to effect step by step movement of said brushes jointly toward their opposite extreme positions providing full negative energization of said first mentioned coil, said brushes at the mid-point of their complete range of travel being subjected to substantially zero potential so that no current will be supplied to said first mentioned coil, means comprising a pair of pushbutton switches selectively operable manually to provide for operating energization of one or the other of said solenoids, means comprising a normally open switch adapted to be closed automatically upon operating movement of either of said solenoid cores, a normally closed electromagnetically operable relay adapted to be energized upon each closure of said last mentioned switch, said relay when opened being adapted to effect deenergization of either of said solenoid coils to provide for resetting of its respective pawl and reopening of said normally

open switch, said switch when reopened effecting interruption of the energizing circuit of said relay, and said relay when deenergized and closed providing for reenergization of the active solenoid coil, whereby a repeated operation of its associated pawl is effected.

11. In a reversing rheostat, in combination, a multiplicity of stationary contact segments arranged in a straight line in fixed spaced relationship to each other, a multiplicity of resistance sections the terminals of which are connected to said contact segments in series relationship to each other, a pair of current supply lines respectively connected to the opposite end contact segments, a pair of contact brushes slidably engageable with said contact segments at opposite side edges thereof, a translating device including a coil the terminals of which are connected to the respective brushes, each of said contact brushes being movable into and out of engagement with all of said contact segments selectively, means for effecting movement of said contact brushes simultaneously in opposite directions from each end contact segment to the other, said means comprising a pair of oppositely threaded shafts, traveling nuts on said shafts, each nut having one of said brushes attached thereto for movement therewith, means for effecting intermittent rotation of said shafts jointly in one direction or the other, said means comprising a third shaft and gearing between the same and said shafts first mentioned, a pair of oppositely toothed ratchet wheels non-rotatably attached to said third shaft, a solenoid including a coil, a core and a pawl associated with each of said ratchet wheels, said pawls being normally biased to positions affording clearance for the respective ratchet wheels, one of said solenoids being adapted upon intermittent energization of its coil to effect step by step movement of said brushes jointly toward the respective extreme positions thereof providing full positive energization of said first mentioned coil, the other solenoid when intermittently energized being adapted to effect step by step movement of said brushes jointly toward their opposite extreme positions providing full negative energization of said first mentioned coil, said brushes at the mid-point of their complete range of travel being subjected to substantially zero potential so that no current will be supplied to said first mentioned coil, means comprising a pair of pushbutton switches selectively operable manually to provide for operating energization of one or the other of said solenoids, means comprising a normally open switch adapted to be closed automatically upon operating movement of either of said solenoid cores, a normally closed electromagnetically operable relay adapted to be energized upon each closure of said last mentioned switch, said relay when opened being adapted to effect deenergization of either of said solenoid coils to provide for resetting of its respective pawl and reopening of said normally open switch, said switch when reopened effecting interruption of the energizing circuit of said relay, said relay when deenergized and closed providing for reenergization of the active solenoid coil, whereby a repeated operation of its associated pawl is effected, and adjustable means associated with said relay to delay reclosure thereof upon interruption of its energizing circuit, whereby the rate of movement of said brushes jointly by said power operated means may be preselected.

12. In a reversing rheostat, in combination, a multiplicity of stationary contact segments ar-

ranged in a straight line in fixed spaced relationship to each other, a multiplicity of resistance sections the terminals of which are connected to said contact segments in series relationship to each other, a pair of current supply lines respectively connected to the opposite end contact segments, a pair of contact brushes slidably engageable with said contact segments at opposite side edges thereof, a translating device including a coil the terminals of which are connected to the respective brushes, each of said contact brushes being movable into and out of engagement with all of said contact segments selectively, means for effecting movement of said contact brushes simultaneously in opposite directions from each end contact segment to the other, said means comprising a pair of oppositely threaded shafts, traveling nuts on said shafts, each nut having one of said brushes attached thereto for movement therewith, means for effecting intermittent rotation of said shafts jointly in one direction or the other, said means comprising a third shaft and gearing between the same and said shafts first mentioned, a pair of oppositely toothed ratchet wheels non-rotatably attached to said third shaft, a solenoid including a coil, a core and a pawl associated with each of said ratchet wheels, said pawls being normally biased to positions affording clearance for the respective ratchet wheels, one of said solenoids being adapted upon intermittent energization of its coil to effect step by step movement of said brushes jointly toward the respective extreme positions thereof providing full positive energization of said first mentioned coil, the other solenoid when intermittently energized being adapted to effect step by step movement of said brushes jointly toward their opposite extreme positions providing full negative energization of said first mentioned coil, said brushes at the mid-point of their complete range of travel being subjected to substantially zero potential so that no current will be supplied to said first mentioned coil, means comprising a pair of pushbutton switches selectively operable manually to provide for operating energization of one or the other of said solenoids, means comprising a normally open switch adapted to be closed automatically upon operating movement of either of said solenoid cores, a normally closed electromagnetically operable relay adapted to be energized upon each closure of said last mentioned switch, said relay when opened being adapted to effect deenergization of either of said solenoid coils to provide for resetting of its respective pawl and reopening of said normally open switch, said switch when reopened effecting interruption of the energizing circuit of said relay, said relay when deenergized and closed providing for reenergization of the active solenoid coil, whereby a repeated operation of its associated pawl is effected, adjustable means associated with said relay to delay reclosure thereof upon interruption of its energizing circuit, whereby the rate of movement of said brushes jointly by said power operated means may be preselected, and said adjustable means comprising a condenser and a variable resistance connected in a closed loop with the coil of said relay to insure operating energization of the latter for a predetermined period of time after interruption of the normal energizing circuit thereof in the manner aforementioned.

13. In a reversing rheostat, in combination, a multiplicity of fixed contact segments arranged in a straight line in spaced relationship to each other, a pair of contact brushes on opposite sides of said contact segments and movable simultaneously in opposite directions respectively from each extreme contact segment toward the other, a multiplicity of resistance sections associated with said contact segments, said extreme contact segments being respectively connected with opposite poles of a source of current supply, a translating device including a winding the terminals of which are connected with the respective brushes, a pair of traveling nuts to which said brushes are respectively attached, a pair of oppositely threaded shafts with which said nuts are respectively associated, power operated electrical means common to said shafts for effecting rotation thereof jointly in one direction or the other, means including a pair of pushbutton switches operable selectively to effect operation of said power operated means in one direction or the other, and means including a cam operated switch and an electromagnetically operable relay associated with said power operated means to insure operation thereof intermittently in each direction respectively to thereby insure movement of said brushes jointly in a step by step manner.

30 14. In a reversing rheostat, in combination, a multiplicity of fixed contact segments arranged in a straight line in spaced relationship to each other, a pair of contact brushes on opposite sides of said contact segments and movable simultaneously in opposite directions respectively from each extreme contact segment toward the other, a multiplicity of resistance sections associated with said contact segments, said extreme contact segments being respectively connected with opposite poles of a source of current supply, a translating device including a winding the terminals of which are connected with the respective brushes, a pair of traveling nuts to which said brushes are respectively attached, a pair of oppositely threaded shafts with which said nuts are respectively associated, power operated electrical means common to said shafts for effecting rotation thereof jointly in one direction or the other, means including a pair of pushbutton switches operable selectively to effect operation of said power operated means in one direction or the other, means including a cam operated switch and an electromagnetically operable relay associated with said power operated means to insure operation thereof intermittently in each direction respectively to thereby insure movement of said brushes jointly in a step by step manner, said relay having a set of normally closed contacts, a condenser and a rheostat connected in series with each other in a closed loop including the operating winding of said relay, said condenser and said rheostat coacting with the operating winding of said relay to delay reclosure of the latter after interruption of the normal energizing circuit of said winding by said cam operated switch, and said rheostat being adjustable to vary at will within a given range the time delay afforded by said relay.

EDWIN N. LIGHTFOOT.
